DESIGN FOR A BIB OR SIMILAR ARTICLE

Mathilde T. Fadie, Oakland, Calif.

Application August 23, 1938, Serial No. 79,518

Term of patent 3½ years

To all whom it may concern:

Be it known that I, Mathilde T. Fadie, a citizen of the United States, residing at the city of Oakland, county of Alameda and State of California, have invented a new, original, and ornamental Design for a Bib or Similar Article, of which the following is a specification, reference being had to the accompanying drawing, forming part thereof.

Figure 1 is a front view of a bib, showing my new design; and

Figure 2 is a back view of the same.

The design comprises a bib of the specific contour disclosed, the rounded front portion of which has a semi-circular pocket across the bottom thereof and the short cap sleeves of which merge into the V-shaped rear sections, as shown, the outer edges of the bib and the top of the pocket being outlined with a relatively narrow border.

I claim:

The ornamental design for a bib or similar article, substantially as shown and described.

MATHILDE T. FADIE.
